MECHANISM FOR PROTECTING THREAD
SHEARING REVOLVERS

Willie Leo Lafond, Woonsocket, R. I., assignor to
Manville Jenckes Corporation, Manville, R. I.,
a corporation of Delaware

Application December 4, 1943, Serial No. 512,990

7 Claims. (Cl. 26—17)

This invention relates to mechanism for protecting thread shearing revolvers. More particularly it provides mechanism for detecting pieces of metal in a travelling web of cloth and then displacing the revolver and the web relatively to permit the piece of metal to pass the revolver without contacting it and thus without danger of damage being done to the revolver by the piece of metal.

Thread shearing revolvers are expensive as to first cost and are expensive to recondition when a cutting edge becomes nicked or otherwise damaged. Yet any slight nick or imperfection in a cutting edge necessitates such expensive reconditioning of the revolver because the imperfection in the cutting edge produces an imperfection in the sheared cloth. It is important therefore to protect the revolver against contact with pieces of metal which not infrequently get into the cloth. A needle or a metal fragment accidentally may find its way into the cloth and pass unnoticed to the shearing region. If the revolver and cloth continue in shearing relation when the metal passes, the result almost certainly will be a damaged revolver. In addition to the cost to recondition such a damaged revolver, there is involved a loss of time and labor while a new or reconditioned revolver is substituted for the damaged one.

It is an object of my present invention to avoid the possibility of pieces of metal being carried in a web of cloth into contact with the thread shearing revolver, thus ensuring against injury to the revolver from this source.

Another object is to combine my revolver protecting mechanism with a seam protecting mechanism in a manner to utilize many parts in common, the two said protecting mechanisms being connected in parallel in an electric circuit which is responsive both to a detected cloth seam and a detected piece of metal in the cloth.

A feature is that the revolver protector may be in the form of an attachment which simply and economically may be applied to already installed thread-shearing machines.

Still another object is to employ a multiple plate contact metal-detector unit designed to detect any piece or particle of metal having size capable of nicking a cutting edge of a revolver by contact therewith.

The mentioned objects and results are attained by providing in a machine having a revolver for shearing threads of cloth means actuated by a piece of metal covered by the cloth and capable

of displacing the revolver and cloth relatively out of thread-shearing relation, maintaining them out of such relation during a predetermined time interval, and permitting their return to shearing relation at the expiration of the interval. Combined therewith, at a predetermined distance in advance of the shearing position, I provide a bank of separated electric contacts over which the strip of cloth passes on its course to the shear.

10 The contacts, closely associated with thin insulation between them extend throughout the breadth of the cloth strip and each of alternate ones of the contacts constitutes a terminal of an open circuit to electrically operated means for causing relative movement of the revolver and cloth. Each of the others of the contacts constitutes a second terminal of that open circuit. Consequently, if a piece or fragment of metal in the cloth bridges across any adjacent two of the contacts, the circuit will be closed to initiate relative displacement of the revolver and cloth at the shearing position.

Spaced slightly away from the bank of contacts as above described is a plate between which and 25 the contacts the cloth must pass on its course to the shearing position. The plate normally is in position holding open a switch in the circuit to said electrically operated means. The plate however is yieldable in direction away from the bank of contacts and when it is moved away from the contacts by the passage of a cloth seam between the plate and the contacts, the switch is permitted to close and establish a circuit through the electrically operated means and thereby cause 30 the revolver and cloth to move relatively out of shearing relation, while the detected seam passes.

The best mode in which I have contemplated applying the principles of my invention is shown in the accompanying drawings, but these are to 40 be deemed merely illustrative because it is intended that the patent shall cover, by suitable expression in the appended claims, whatever features of patentable novelty exist in the invention disclosed.

45 In the accompanying drawings:

Figure 1 is an end elevation of a float thread shearing machine embodying features of my invention;

Figures 2 is a similar view of the upper part of 50 Figure 1, on a larger scale, the right hand portion of the view being in medial vertical section;

Figure 3 is a top plan of the detector mechanism of Figures 1 and 2 with the guide roll and the cloth omitted for clearness of showing;

Figure 4 is a detail vertical sectional view on 4-4 of Figure 3, on a larger scale;

Figure 5 is an end view, looking from the left in Figure 1, showing the mechanism for actuating the shear-carrying frame, portions being in vertical section;

Figure 6 is a diagrammatic view of the electrical circuits; and

Figure 7 is an elevation of the latch actuating mechanism of the control switch, the supporting wall being in section.

Referring to the drawings, my invention is shown applied to a float thread shearing machine. As best seen in Figure 1, a strip of cloth 10 travels in the direction of the arrows around the guide rolls 12, 14, 16 and 18 to the usual fixed cloth rest 20 at the shearing position, whence, after being acted upon by the shear, it passes down and around guide rolls 22, 24, 26, 28 and 30, to be eventually wound up as a roll. The guide rolls and the cloth rest 20 are suitably mounted on the frame of the machine, indicated generally at 32, 34. Guide roll 26 is power driven and constitutes the means for drawing the web 10 through the machine. It may be driven by a suitable connection from the main shaft 36 which in turn may be driven from any suitable source of power.

The run of the cloth between guide rolls 16, 18 passes between presser element 38 and a rotary brush 40 on shaft 42, the element 38 engaging the cloth from the rear and the brush acting on that side of the cloth having the float threads, to condition the threads for the shearing operation. Brush shaft 42, suitably mounted on frame 32 as at 44 (Figure 2) is driven from shaft 36, but in opposite direction, by means of the crossed belt 46 trained over pulleys 48, 50 and 52, the first two being on shafts 36 and 42 respectively, and pulley 52 being an idler.

The shear comprises a usual revolver 54 coacting with a usual shear blade 56 (Figure 2) which is fixed relative to the revolver. As herein represented, both the revolver 54 and the blade 56 are mounted on the tiltable frame 58 which is pivoted at 60 on the fixed frame part 34 of the machine. The revolver is driven from shaft 36 through the belt and pulley drive connections 62, 64 and 66.

A lever 68 is pivoted at 70 on the frame 32 of the machine and has one end engaging the lower end of the revolver carrying frame 58. The other end of lever 68 carries a roller 72 which rides on the periphery of a cam 74 (Figures 1, 2 and 5), which is free on the projecting shaft 27 of constantly rotating guide roll 26, as best seen in Figure 5. A spur gear 76, also free on the shaft 27, is secured to the cam as by screws 78 (Figure 5) and meshes with one spur gear 80 of an integral pair 80, 82 on an underneath shaft 84. The other spur gear 82 of the integral pair meshes with a spur gear 86 which is free on shaft 27 and has a clutch face 88++ adapted for coaction with a clutch element 90 which is slidably keyed as at 92 on shaft 27. Hence, when the rotating clutch element 90 is shifted into engagement with the clutch face 88 of gear 86, cam 74 rotates and its high side elevates the roller end of lever 68 and depresses its other end to rock the shear carrying frame 58 counterclockwise about its pivot 60, thereby to swing the revolver 54 and shear blade 56 away from shearing relation to the cloth 10 where it passes over the cloth rest 20. When roller 72 on lever 68 rides from the high to the low side of cam 74, the shear frame 58 is permitted to resume its normal position under the

influence of gravity, to bring the shear elements back into thread shearing relation to the cloth.

My invention provides means for moving the revolver 54 away from the cloth rest 20 whenever a seam or a piece of metal comes along in the cloth. In both instances the seam or metal is detected before it reaches the cloth rest and in time for the revolver to be displaced while the metal or seam passes by the rest. I will first describe the action of my protecting means when a seam is approaching the revolver.

As best seen in Figures 3 and 4, the cloth 10 passes vertically between a plate 94 and a bank of contact elements 96 indicated generally at 96. Both plate 94 and the elements 96 have length approximately equal to the width of the cloth strip, as seen in the plan view of Figure 3, and the space between them approximates the thickness of the cloth 10. The plate 94 is actuated by a seam 11 to effect displacement of the revolver, whereas the contact elements 96 are depended upon to detect a piece of metal and bring about the displacement of the revolver.

Plate 94 is yieldable in direction away from the bank of elements 96 so that a seam attempting to pass between them must displace plate 94 to the left (Figures 1, 2 and 4) in order to pass. Such a displacement of plate 94 by a seam permits a presser element 98 (Figure 3) to follow it with the result that an electric switch indicated generally at 100, which normally is held open, is permitted to close, thereby to close an electric circuit through solenoid 102 (Figures 1, 2 and 6), which initiates actuation of clutch element 90 into driving relation with clutch face 88 of gear 86 to cause rotation of cam 74, rocking of lever 68 and counterclockwise movement of the shear-carrying frame 58.

The bank of contact elements indicated generally at 96 and between which and plate 94 the cloth 10 passes on its approach to guide roll 18 comprises a series of metal plates 126, 128 alternately arranged in multiple above and below a supporting element 130, which preferably is of insulation material, and by which the bank of contact elements may be mounted on the frame of the machine. Thin sheets 132 of insulation material separate the plates 126, 128 from each other, and the plates and insulation sheets are clamped together and to the supporting element 130 by bolts 134, one at each end of the bank or stack and each having a nut 136 on its opposite ends. Each bolt 134 extends through all of the elements of the stack and has a surrounding insulating bushing 138 maintaining it out of electrical contact with all of the plates 126, 128. The bushing at its lower end has an integral flange 139 intervening between nut 136 and the lower plate, and an insulating strip 140 intervenes between the upper nut 136 and the top plate and carries the terminal screws 142. All of the plates 126 are electrically connected together, and all of the plates 128 similarly are electrically connected together. Figure 6 suggests the electrical interconnection of the individuals of both sets of plates, where thin U-strips 144 of metal bridge from one plate 126 to the next plate 126 in the stack and the bridges of the U-strips are shaped to contact each other, and likewise between plates 128.

As shown in Figure 6 the respective sets of plates are connected in parallel with the contacts of the switch 100 associated with the seam detecting mechanism heretofore described. Hence whenever a metal piece or fragment in the cloth

10 bridges two of the metal plates 126, 128, the circuit through the solenoid 102 is closed in the same manner that the relay circuit is completed when a seam is detected and switch 100 is closed. Accordingly in what follows, the resulting action following the energization of solenoid 102 is the same regardless of whether a seam or a piece of metal is detected.

The energization of solenoid 102 causes a lever 103 (Figure 7) to swing to the left and pull a rod 119 with it. This rod passes somewhat loosely through a hole in the lower end of a latch bar 118 that has loose pivotal connection with a switch lever 122 at 123. On the latch bar 118 is a latch 124 which normally engages the switch lever 122 and holds the latter in such a position that a snap switch 114 is kept open. When the rod 119 is pulled by lever 103 upon energization of solenoid 102, the bar 118 is also swung to the left releasing latch 124 from the lever 122 which thereupon swings to the right, as seen in Figure 2, to close switch 114.

This completes a circuit through a solenoid 112 and causes an armature rod 110 (Figure 5) to be drawn upward and swing a bell crank lever 108 about its pivot 109. The bell crank is pivotally connected at 107 to one end of a lever 104 which is pivoted at 106 and has its other end engaging the clutch element 90. Accordingly energization of solenoid 112 effects the movement of clutch element 90 into engagement with the other clutch element 88 on gear 86 and brings about the rotation of the latter with results heretofore described.

Promptly upon the seam 11 in the cloth passing the bar 94 the latter returns to its normal position and switch 100 is again opened and solenoid 102 deenergized. Similarly when a piece of detected metal passes beyond the plates 126 and 128 the circuit through solenoid 102 is again opened. When this occurs lever 103 will swing to the right and permit spring 120 to draw the latch bar 118 back against the switch lever 122, but with its latch 124 to the left side of lever 122, as seen in Figure 2.

The latch bar 118, however, is connected by a rod 116 with lever 68 and as the upper arm of the latter swings clockwise, it pulls the latch bar with it so that the latter swings about its pivotal mounting at 123. This causes the latch 124 to slide across the switch lever 122 and eventually, by virtue of the pull of spring 120, to move to the right as seen in Figure 7 and in position to engage switch lever 122. Accordingly as the upper arm of lever 68 swings counterclockwise, the rod 116 pushes the latch bar 118 and with it the switch lever 122 to the left as seen in Figure 2. This effects opening of switch 114 and deenergization of solenoid 112. As a result armature 110 drops bringing about the disengagement of the clutch elements 88 and 90.

The cam 74 is so designed and rotated at a proper speed to effect the separation of the revolver 54 from the cloth rest 20 before the piece of metal or the seam reaches the latter and to maintain this separation just long enough to enable the seam or metal to pass the rest and not make contact with the revolver.

Although I have shown both a metal detector and a seam detector, it is to be understood that either may be used separately. More particularly, when any seam detector is present on an already installed machine, my improved apparatus for detecting metal pieces can be installed without necessarily changing the already present 75 the

seam detecting mechanism. Furthermore, even though I have used for illustration a machine having only one revolver, my invention may be applied to machines having more than one revolver.

I claim as my invention:

1. In a machine for shearing surface threads from a strip of cloth, having a cloth rest and a rotary cutter between which the strip of cloth passes at the shearing position, electrically controlled means for displacing the cloth and the rotary cutter relatively out of shearing relation to each other, comprising a device having terminal plates electrically insulated from one another, extending across the path of travel of the cloth, connected in the electrical circuit of said electrically controlled means and over which approximately the full breadth of the strip of cloth passes on its course to the shearing position, said extended plates being responsive to contact simultaneously with any piece of metal carried by the cloth for closing said electrical circuit, thereby to cause relative displacement of the cloth and the rotary cutter at the shearing position.

2. In a machine for shearing surface threads from a strip of cloth, having a cloth rest and a rotary cutter between which the strip of cloth passes at the shearing position, electrically controlled means for displacing the cloth and the rotary cutter relatively out of shearing relation to each other, comprising a device having terminal plates electrically insulated from one another, extending across the path of travel of the cloth, connected in the electrical circuit of said electrically controlled means and over which approximately the full breadth of the strip of cloth passes on its course to the shearing position, said plate being responsive to contact simultaneously with any piece of metal carried by the cloth for closing said electrical circuit, thereby to cause relative displacement of the cloth and the rotary cutter at the shearing position; and means for maintaining said displacement for a time interval predetermined to permit the piece of metal to pass the shearing position.

3. In a machine for shearing surface threads from a strip of cloth, having a cloth rest and a rotary cutter between which the strip of cloth passes at the shearing position, rotary cutter relatively out of shearing relation to each other, comprising mechanism responsive to passage of a cloth seam, and a device having terminal plates electrically insulated from one another, extending across the path of travel of the cloth and responsive to contact simultaneously with any piece of metal carried by the cloth, said mechanism and said plates being in opposed slightly spaced relation in advance of the shearing position, and said strip of cloth passing between them on its course to the shearing position, and said mechanism and said plates being connected in parallel in the electric circuit of said electrically controlled means, whereby either a cloth seam or a piece of metal passing between said mechanism and said plates can cause operation of said electrically controlled means to effect relative displacement of the cloth and the rotary cutter at the shearing position.

4. In a machine for shearing surface threads from a strip of cloth, having a cloth rest and a rotary cutter between which the strip of cloth passes at the shearing position, a series of metal plate elements slightly spaced apart and insulated from each other and set edgewise beside the path of travel of the cloth at a location in advance of the shearing position; said plates alternately

being electrically connected together to provide a positive set of plate contacts and a negative set of plate contacts extending approximately throughout the full breadth of the strip of cloth and in contact with which said cloth passes on its course to the shearing position, said sets of plates being connected in an open electric circuit which is closable by a piece of metal carried by the cloth and bridging any two adjacent plates, and means responsive to a closing of said circuit for displacing the cloth and the rotary cutter relatively out of shearing relation to each other at the shearing position, and for maintaining the displacement for a predetermined time interval long enough to permit the piece of metal to pass the shearing position.

5. In a machine for shearing surface threads from a strip of cloth, having a cloth rest and a rotary cutter between which the strip of cloth passes at the shearing position, electrically responsive means for moving the rotary cutter out of shearing relation to the cloth, and a metal detecting device having terminal plates electrically insulated from one another and electrically connected to said electrically responsive means, said plates extending across the entire strip of cloth in the path of travel of the cloth to the shearing position and responsive to contact simultaneously with a piece of metal carried by the cloth and operative to cause operation of said electrically responsive means.

6. In a machine for shearing surface threads from a strip of cloth, having a cloth rest and a

rotary cutter between which the cloth passes at the shearing position, means for detecting metal which may be carried by the cloth and for causing relative displacement of the cloth and rotary cutter out of shearing relation until the detected metal passes the shearing position, said means comprising a stack of metal plates spaced slightly apart, and having thin insulation between adjacent plates, said stack being set with aligned edges of the plates beside the path of travel of the cloth on its course to the shearing position, said plates being connected in an electric circuit with each adjacent pair of plates constituting respectively a positive and a negative terminal of a bank of gaps in said circuit, the bridging of any of which gaps by a piece of metal carried by the cloth will close said electric circuit, and means responsive to a closing of said circuit for displacing the cloth and rotary cutter relatively out of shearing relation.

7. A metal detecting attachment for cloth shearing machines, comprising a stack of metal plates clamped flatwise together with edges of the plates aligned at one side of the stack; each said plate being insulated from adjacent plates by a thin sheet of insulation material, and adjacent plates throughout the stack being electrically connected to different ones of two terminals, and means for mounting the stack on a cloth shearing machine with the aligned edges of the plates close beside and transversely of the path of travel of the cloth to the shearing position.

WILLIE LEO LAFOND.
